UNITED STATES PATENT OFFICE.

CHARLES E. WARD, OF CHARLESTON, WEST VIRGINIA.

MEANS FOR APPLYING POWER TO SIDE-WHEEL VESSELS.

Application filed June 24, 1926. Serial No. 118,252.

This invention relates to a means for applying power from high speed engines to the paddles of side wheel boats, and has for its object to provide a mechanism which will be simple in construction, certain in operation, and more efficient in use than those heretofore proposed.

With these and other objects in view, the invention consists in the novel details of construction and combinations of parts more fully hereinafter disclosed and particularly pointed out in the claims.

Referring to the accompanying drawings forming a part of this specification, in which like numerals designate like parts in all the views:

Fig. 1 is a diagrammatic longitudinal sectional view of a portion of a side wheel boat with my invention applied thereto;

Fig. 2 is a sectional plan view of the parts shown in Fig. 1;

Fig. 3 is a diagrammatic view illustrating the application of power to the large gear wheel, showing the power cranks at right angles to each other;

Fig. 4 is a plan view of a slightly modified form of the invention wherein bevel gears are used in the place of the planetary gearing shown in Figs. 1 and 2;

Fig. 5 is a side elevational view of the parts shown in Fig. 4;

Fig. 6 is a transverse sectional view taken on the line 6—6 of Fig. 5 and looking in the direction of the arrows;

Fig. 7 is a detail perspective view of a bearing for the paddle wheel shaft; and

Fig. 8 is a diagrammatic side view of the construction shown in Figs. 4 to 6 illustrating the means of supporting the outboard bearing for the paddle wheel.

As is well known, it is very desirable in driving the paddle wheels of side wheel vessels, to maintain a steady propulsive effort on the paddles at all times; to this end it has been found advantageous to employ more than one engine, and further, it is very desirable to so connect the engine power with the paddle wheels, that the engines cannot stop on a dead center. The employment of high speed engines of course is to be desired, and therefore it is most essential that the drive connections be so constructed and arranged as to give full bearing contact between the gears, and a balanced drive with a minimum of mechanical trouble.

Referring more particularly to Figs. 1, 2

and 3, the numeral 1 indicates any suitable frame work supporting a deck or base 14, 2 a shaft on which the paddle wheel 3 is rigidly mounted, 4 a large planetary drive gear rigid with the shaft 2, 5 a small planetary driving gear meshing with the larger drive gear 4 on one side thereof, and 6 another small planetary driving gear meshing with the said large gear 4 on the other side thereof. That is to say, the driving pinions 5 and 6 are on opposite sides of the vertical plane of the axis of the wheel shaft 2, but it is to be understood that they may be either diametrically opposed or relatively closely spaced. Further, it is within the scope of this invention to have the three gears 4, 5 and 6 all within the same plane, or the plane of each pinion may be inclined to the plane of the main drive gear 4, according to the position of the engines and their connecting parts. The small gears 5 and 6 are mounted on the shafts 7 and 17 respectively journalled in suitable bearings 8 and 18 respectively carried by the supports or engine beds 9 and 19 on which the high speed engines 10 and 11 respectively are mounted.

The engine 10 is connected to the shaft 7 of the small gear 5 by means of the crank 12 while the engine 11 is connected to the shaft 17 of the small gear 6 by means of the crank 13. The cranks 12 and 13 are placed at an angle to each other, so that it is not possible while both engines are running, for either to get on a dead center.

By thus dividing the work delivered to the large gear 4 and applying it at two or more points, as indicated, on the circumference of said gear 4, one is enabled to obtain the advantage of more uniformly applied power, and therefore one is enabled to employ lighter gear wheels, higher speed engines, and more economical engines than could be used if the power were all transmitted through one small pinion or gear wheel.

Of course, the engines could be of any suitable type, and could be either horizontal or vertical as desired. Further, the gear ratio is so chosen that the engine cranks will always remain at an angle to each other, and therefore, it will not be possible for them to get on a dead center. It is to be understood that each or all of the paddle wheels of the vessel will be equipped with the driving mechanism above disclosed.

Referring more particularly to Fig. 4 illustrating a modification of the drive mechanism described above, it will be seen that the paddle wheel 20 is mounted on a shaft 21 the outer end of which rotates in a suitable bearing 22 rigidly secured to the wheel-beam or outboard framing 23 which may be of channel iron or any other suitable strong and well known construction. Each paddle wheel rotates in the box or recess 24 provided therefor all as will be readily understood. The inboard end of the wheel shaft 21, see Figs. 4, 5 and 6, is mounted for rotation in a bearing generally indicated by the numeral 26 and comprising an upper half 27 and a lower half 28 so constructed that when said halves are put together there will be disposed on either side of said bearing a trunnion 29. That is to say, each trunnion is halved as is particularly illustrated in Fig. 7. Each trunnion 29 is adapted to be supported by a bracket 30 secured to a suitable base, as the deck 31, by the bolts 32. With particular reference to Fig. 6 it will be noticed that the bearing for each trunnion is split, and that the line of the split is obliquely disposed to the line of separation between the two halves of the trunnion. The purpose of this will be evident, but may be stated as being to prevent undue wearing of the trunnion or its associated bracket upon any rotation of the trunnion 29 in said bracket.

To prevent a longitudinal movement of the wheel shaft 21 in an outboard direction, there is rigidly secured to the inboard end of shaft shaft a suitable thrust collar 35 provided with a ball race 36, said collar adapted to take against the inboard side of the bearing 26 for said shaft. To prevent inboard longitudinal movement of said shaft, there is rigidly secured thereto a large bevel drive gear 40 adapted to mesh with a bevel driving pinion 41 on one side thereof, and a bevel driving pinion 42 diametrically opposed to the pinion 41. That is to say, the driving pinion 41 is rigidly mounted on an intermediate driving shaft 45, the ends of which are supported in the bearings 46 and 47, said bearings being so located on the deck 31 that the shaft 45 is disposed at right angles to the wheel shaft 21. It is further an important feature of this invention that said shaft 45 is disposed coaxially with reference to the trunnions 29 of the bearing 26 supporting the inboard end of said wheel shaft 21. The parts are of such size and so disposed as to allow the driven bevel gear 40 to just clear the said bearing 26 for the wheel shaft 21, and the deck 31 is cut away as at 50 in order that the driven gear 40 may efficiently function.

Adjacent the bearing bracket 47 there is rigidly mounted on the intermediate drive shaft 45 a planetary gear 51 adapted to en-

mesh with a planetary driving pinion 52 rigidly mounted on a main drive shaft 53 (driven from any suitable source of power not shown) mounted in suitable bearings such as 54 and 55 disposed on either side of the pinion 52, said bearings supported by the deck 31.

Thus it will be seen from the foregoing, and with particular reference to Fig. 4, that the power applied to the shaft 53 to rotate the same in the direction of the arrow will, through the planetary gears 52 and 51 cause the intermediate shaft 45 to rotate in the direction indicated, which in turn will rotate the bevel gears 41 and 40 to cause the wheel shaft to be revolved in the direction indicated by the arrow thereon.

On the other side of the driving gear 40 is disposed the bevel drive pinion 42 similar in all respects to the drive pinion 41 and rigidly mounted on an intermediate drive shaft 60 whose ends are mounted for rotation in the brackets 61 and 62. This intermediate shaft 60 likewise carries a rigidly mounted planetary gear 63 enmeshing with a driving pinion 64 rigidly mounted on a drive shaft 65 (driven from a suitable source of power not shown) mounted in the brackets 66 and 67 as clearly illustrated in Fig. 4. The parts 42, 60, 63, 64 and 65 are preferably duplicates of the corresponding parts 41, 45, 51, 52 and 53 although variations are permissible as necessitated by the construction of the vessel. The bearing brackets 61, 62, 66 and 67 are likewise all carried by the deck 31, exactly as were the bearing brackets associated with the diametrically disposed drive mechanism described above. If desired, an additional bearing bracket 70 may be provided for the intermediate drive shaft 45 adjacent the bevel drive pinion 41 and an extra bearing bracket 71 may be provided for the intermediate shaft 60 adjacent the other bevel drive pinion 42. The intermediate drive shaft 60 is likewise positioned rectangularly to the wheel shaft 21, and so mounted that it, too, is coaxial with the trunnions 29 of the wheel shaft bracket 26. The intermediate drive shafts 45 and 60, and the trunnions 29 are all in coaxial alignment for a purpose that will presently appear. Said intermediate shafts being in alignment, the bevel pinion gears 41 and 42 carried thereby will likewise be in alignment, with the result that the driven gear 40 on the shaft 21 will be in mesh with both of said bevel drive pinions 41 and 42 when mounted as shown in the illustrations.

Therefore it is obvious from the foregoing that the driven gear 40, rigid with the shaft 21, will prevent said shaft from axial movement in an inboard direction by its enmeshment with the bevel drive pinions 41 and 42, and that the thrust bearing 35 also rigid with the shaft 21, will prevent an axial movement of said shaft in an outboard di-

rection. The result therefore is that the paddle wheel 20 will be maintained in its correct position at all times in the box or recessed portion 24 provided for said wheel.

5 The wheel beam or outboard framing 23, as stated above, may be of channel iron or any construction affording great rigidity and strength, but with particular reference to Fig. 8, it is to be understood that said out-
10 board framing is to be maintained in rigid relationship with the main framing of the vessel. To accomplish this result, any suitable construction may be utilized, such for example as a main stay 75 the upper end of
15 which is rigidly secured to an upper framing member 76 of the vessel, and the lower end of which is rigidly secured to the wheel beam 23. A similar stay 77 provided below the wheel beam has one end thereof secured
20 to said beam and the other end rigidly secured to any suitable framing member of the hull 78 of the vessel. Thus it will be seen that the wheel beam 23 is strengthened to resist the strains placed thereon during navigation, with the result that the outboard
25 end of the wheel shaft 21 would normally be prevented from vertical movement.

The main advantage obtained by this type of construction over the prior constructions
30 will be obvious, but it might be generally stated as being to positively transmit power to the wheel shaft so long as the engine operates. That is to say, with this construction any displacement of the outboard framing 23 in a vertical direction, will cause the wheel shaft 21 to oscillate about a center lying in the common axis of the trunnions 29 of the wheel shaft bearing 26 and the intermediate drive shafts 45 and 60. But it is
35 to be observed that such a movement of the wheel shaft 21, will not unmesh the driven gear 40 from its driving pinions 41 and 42, but on the other hand, will merely cause the former to move bodily around the latter.
40 Stated in other words, the bearings for the wheel shaft are always in alignment regardless of any vertical movement of the outboard end thereof, for the reason that the inboard bearing is supported by the trunnions 29.
45

Another great advantage obtained by this improved construction is that the thrust collar 35, and the large drive gear 40 are so disposed to either side of the bearing 26 for
50 the wheel shaft 21 that axial movement of the said wheel shaft is prevented. In other words, the main drive gear 40 is maintained in mesh with the driving pinions 41 and 42 by the single thrust collar 35, thus obviating
55 the necessity of a plurality of thrust collars adjacent one of the shaft bearings or a thrust collar at each end of the wheel shaft.

60 Another advantage obtained by this construction lies in the fact that there is provided a balanced drive mechanism. That is

to say, by having a driving pinion on either side of the center of the main drive gear, a more even transmission of power is obtained and the usual strains in starting and stopping are reduced to a minimum. Also, by
65 providing double drives, the strains of each driving mechanism, as well as the total strain on the main drive gear 20, will be reduced approximately 50%.

70 From the foregoing it will therefore be seen that by this invention there is provided a drive mechanism for a vessel utilizing a main driven gear rigidly mounted on a shaft, a pair of driving pinions which are balanced and which mesh with said driven gear on opposite sides thereof. Further, there is provided a plurality of driving cranks connected with said pinions so disposed angularly to each other that all the engines to which they are connected cannot
75 stop on a dead center. Further, it is to be observed that the driving means is such that the pinions will always be maintained in positive mesh with the main drive gear 40, due to the fact that the wheel shaft 21 is
80 prevented from axial movement in either direction as clearly brought out above. This is true even when there is a vertical movement of said wheel shaft 21 which movement, under normal conditions and according to prior constructions, would be capable
85 of throwing the main driven gear out of mesh with its driving pinions with resultant damage to all parts of the drive mechanism.

90 It is further to be observed that by this construction there is provided an outboard bearing at one end of the wheel shaft, which bearing is more or less rigid with the framework of the vessel. At the other end of the wheel shaft there is provided a second bearing which is flexibly mounted.

95 That is to say, the bearing 26 is so constructed with the trunnions 29, that said bearing may be free to rotate in the brackets for said bearing upon any vertical movement of the wheel shaft 21. Lastly, inasmuch as the intermediate drive shafts 45 and 60 carrying the driving pinions 41 and 42, as well as the trunnions 29 are all in coaxial alignment,
100 any vertical movement of the wheel shaft 21 would merely cause the main drive gear 40 to revolve bodily about the driving pinions.

105 In other words, no matter what degree of vertical movement there was to the wheel shaft 21, the main drive gear 40 would always be kept in mesh with the driving pinions 41 and 42. In this connection it is to be especially observed that the center line of the intermediate shafts 45 and 60 and the trunnions 29, and the center line of the wheel shaft 21 are rectangularly disposed in
110 the same plane, and that this relationship
115 is always maintained even though there is vertical movement imparted to the wheel shaft 21.

120

125

It is obvious that those skilled may vary the details of construction as well as the arrangements of parts without departing from the spirit of the invention, therefore, it is 5 not desired to be limited to the foregoing except as may be required by the claims.

What is claimed is:—

1. In a vessel the combination of a paddle wheel; a shaft on which said wheel is mounted; an outboard bearing for one end of said shaft; a main driven gear rigid with said shaft; balanced driving means to rotate said gear; and means cooperating with the inboard bearing for the other end of said 15 shaft to maintain positive driving connections between said driving means and said gear.

2. In a vessel the combination of a paddle wheel; a shaft on which said wheel is mounted; an outboard bearing rigidly secured to the framework of the vessel for one end of said shaft; a main driven gear rigid with said shaft; balanced driving means to rotate said gear; and means including a flexibly 25 mounted inboard bearing to maintain positive driving connections between said driving means and said gear.

3. In a vessel the combination of a paddle wheel; a shaft on which said wheel is mounted; an outboard bearing for one end of said shaft; a main driven gear rigid with said shaft; balanced coaxial driving means to rotate said gear; and means to maintain positive driving connections between said driving 35 means and said gear including an inboard bearing for the other end of said shaft

adapted for rotation about said coaxial driving means.

4. In a vessel the combination of a paddle wheel; a shaft on which said wheel is mounted; a rigid outboard bearing for one end of said shaft; a main driven gear rigid with said shaft disposed near the other end of said shaft; means to drive said gear including a pair of pinions whose axes are in alignment; and means to maintain positive driving connections between said pinions and said gear including an inboard bearing for the other end of said shaft having an axis of rotation in coalignment with the axes of 45 said driving pinions whereby said main drive gear will partially revolve bodily around said pinions upon movement of said shaft in a vertical direction.

5. In a vessel the combination of a paddle wheel; a shaft on which said wheel is mounted; a rigid outboard bearing for one end of said shaft; a main driven gear rigid with said shaft disposed near the other end of said shaft; means to drive said gear including a pair of pinions whose axes are in alignment and in the same plane with the axis of said shaft; and means to maintain positive driving connections between said pinions and said gear including an inboard bearing for the other end of said shaft disposed between said gear and a thrust-collar rigidly secured to said shaft.

In testimony whereof I affix my signature.

CHARLES E. WARD.
